(57) **CLAIM**

I claim the ornamental design for a metatarsal dome, as shown and described.

DESCRIPTION

FIG. 1 is a perspective view of the top, front and side of a metatarsal dome.

FIG. 2 is a rear view of the metatarsal dome of FIG. 1.

FIG. 3 is front view of the metatarsal dome of FIG. 1.

FIG. 4 is a first side view of the metatarsal dome of FIG. 1.

FIG. 5 is a second side view of the metatarsal dome of FIG. 1.

FIG. 6 is a top view of the metatarsal dome of FIG. 1.

(Continued)

FIG. 7 is a bottom of the metatarsal dome of FIG. 1.
FIG. 8 is a perspective view of the bottom, rear and side of the metatarsal dome of FIG. 1.
FIG. 9 is a perspective view of the top, front and side of a metatarsal dome.
FIG. 10 is a rear view of the metatarsal dome of FIG. 9.
FIG. 11 is front view of the metatarsal dome of FIG. 9.
FIG. 12 is a first side view of the metatarsal dome of FIG. 9.
FIG. 13 is a second side view of the metatarsal dome of FIG. 9.
FIG. 14 is a top view of the metatarsal dome of FIG. 9.
FIG. 15 is a bottom of the metatarsal dome of FIG. 9.
FIG. 16 is a perspective view of the bottom, rear and side of the metatarsal dome of FIG. 9.
FIG. 17 is a perspective view of the top, front and side of a metatarsal dome.
FIG. 18 is a rear view of the metatarsal dome of FIG. 17.
FIG. 19 is front view of the metatarsal dome of FIG. 17.
FIG. 20 is a first side view of the metatarsal dome of FIG. 17.
FIG. 21 is a second side view of the metatarsal dome of FIG. 17.
FIG. 22 is a top view of the metatarsal dome of FIG. 17.

FIG. 23 is a bottom of the metatarsal dome of FIG. 17.
FIG. 24 is a perspective view of the bottom, rear and side of the metatarsal dome of FIG. 17.
FIG. 25 is a perspective view of the top, front and side of a metatarsal dome.
FIG. 26 is a rear view of the metatarsal dome of FIG. 25.
FIG. 27 is front view of the metatarsal dome of FIG. 25.
FIG. 28 is a first side view of the metatarsal dome of FIG. 25.
FIG. 29 is a second side view of the metatarsal dome of FIG. 25.
FIG. 30 is a top view of the metatarsal dome of FIG. 25.
FIG. 31 is a bottom of the metatarsal dome of FIG. 25; and, FIG. 32 is a perspective view of the bottom, rear and side of the metatarsal dome of FIG. 25.
The ornamental design that is claimed is shown in the drawings as solid lines and surfaces having surface shading. The surface shading shown in thin, solid lines is for purposes of illustrating the character and/or contour of the surfaces of the claimed invention and does not indicate surface texture, material, contrast in material, or color, nor forms any part of the claimed design.
